UNITED STATES PATENT OFFICE.

GEORGE W. DODGE, OF LIVERMORE FALLS, MAINE, ASSIGNOR TO FRICTION PULLEY AND MACHINE WORKS, OF SANDY HILL, NEW YORK.

CONTROLLING-VALVE.

SPECIFICATION forming part of Letters Patent No. 614,798, dated November 22, 1898.

Application filed July 8, 1897. Serial No. 643,791. (No model.)

To all whom it may concern:

Be it known that I, GEORGE W. DODGE, of Livermore Falls, county of Androscoggin, State of Maine, have invented an Improvement in Controlling-Valves, of which the following description, in connection with the accompanying drawings, is a specification, like letters and figures on the drawings representing like parts.

10 This invention has for its object the production of a simple, strong, efficient, and durable balanced valve particularly adapted for use in controlling hydraulic elevators, the feed-cylinders of pulp-grinders, and for many other purposes.

In the valve to be herein described the valve-seats are so arranged relatively to the valves that the movement of the latter is in a direct line toward and from the seats, obviating the wearing action inevitable in apparatus wherein there is any lateral or rubbing movement, so that my novel valve is durable in the highest degree even under the most exacting conditions.

25 I have herein shown my invention embodied in a four-way valve, the valve-case having main inlet and exhaust ports and two delivery-ports, the arrangement of the valves and seats being such that communication between the inlet and a delivery port is effected simultaneously with communication between the other delivery-port and the exhaust. The valve-faces proper are made of suitable yielding material, preferably rubber, held in place 30 in a novel and secure manner, yet permitting ready removal when worn.

Figure 1 is a plan view of a four-way valve embodying my invention, the top or cover of the valve-case being removed. Fig. 2 is a 40 horizontal sectional view thereof, taken on the irregular line $\alpha\alpha'$, Fig. 3. Fig. 3 is a transverse sectional view thereof on the line $\alpha'\alpha'$, Fig. 2, looking toward the right, with the cover on and valve-actuator in place. Fig. 45 4 is an enlarged diametral section of one of the valve-shells, and Fig. 5 is a detached under side view of the actuator shown in Figs. 1 and 3.

The valve-case $A^\times$ is divided by walls or partitions $a a' a''$ into chambers A , A' , A'' , and

A^3 , the latter having discharge ports or ducts $D D'$, respectively, which in practice are suitably connected with the working cylinder of the apparatus with which the controlling-valve is to be used.

55

The main shaft 1 opens into the chamber A , and the exhaust E leads from the chamber A' , said chambers being located on opposite sides of the partition a and between the "discharge-chambers" $A^2 A^3$, as they may be termed.

60 Preferably threaded ports in the walls a' and a'' receive the oppositely located and alined annular valve-seats $b b'$ within the inlet-chamber A , and a valve-spindle $b^\times$, extended through the valve-ports, has bearings for its ends in removable glands or boxes 55 , shown as screwed into threaded openings in the end walls of the case $A^\times$.

65 The spindle $b^\times$ is threaded between the valve-seats at b^2 to receive an internally-threaded sleeve b^3 , provided with disks b^4 , having outwardly-extended annular flanges b^5 , each disk, with its flange, forming a valve-shell.

75

An annular rib or projection 3 is formed on the interior of each flange and an opposite rib 4 on the sleeve b^3 , and a ring of rubber or other suitable yielding material 10 is forced into each valve-shell, being retained securely 80 therein by the ribs or projections 3 and 4.

70 The rings 10 preferably project slightly beyond the flanges b^5 , forming yielding valve-faces to coöperate with the seats b and b' , as clearly shown in Figs. 1 and 2, the yielding character of the faces serving to tightly and completely close the valve-ports when seated.

85 By rotating the sleeve b^3 on the spindle when setting up the valves are adjusted relatively to the seats to correspond with the stroke of the spindle $b^\times$.

It will be obvious that communication between the inlet-chamber A and the delivery or discharge ports D and D' is controlled by the movement of the valves described.

95

On the outer sides of the walls $a a' a''$ annular valve-seats $c c'$ are provided for the ports, the seats being located in the discharge-chambers $A^2 A^3$, respectively, the ports communicating with the exhaust-chambers A' , 100

and a longitudinally-movable valve-spindle c^x is extended through said ports into bearing-boxes 6 6, screwed into the end walls of the valve-case. The spindle is threaded adjacent each port, as at 2, to receive thereon like valve-shells, (shown separately in Fig. 4,) each consisting of a threaded hub c^2 , a disk c^3 , and an annular flange c^4 , the inner faces of said flange and hub having, respectively, ribs or annular projections 8 9. Yielding rings 10 described are forced into the shells, projecting beyond the hubs and flanges thereof to form the valve-faces held in place by the ribs 8 9.

15 When the valve-shells are adjusted on the threaded portions 2 of the spindle, they are secured by suitable check-nuts n , the valves comprising the shells and yielding faces 10 controlling the communication between A^2 20 A^3 and the exhaust-chamber A' .

The spindles are herein shown as provided with annular enlargements or rings 7, to be engaged by a yoke f , connecting the spindles $b^x c^x$ to move them longitudinally in unison, 25 said yoke having, as herein shown, a lug f' on its upper face to loosely enter a slot g' in the base of a rock-shaft g , supported in a packing-box or gland g^x on the cover B, a handle g^2 operating the rock-shaft. The rock- 30 shaft is at one side of the lug f' , so that rotative movement of the former will move the yoke in one direction or the other.

From the foregoing description and the drawings detailed description of the operation of the valve mechanism will be unnecessary, it being evident that reciprocation of the valve-spindles will alternately connect the delivery-ports D D' with the inlet and exhaust. 35

40 As soon as the pressure upon the several valves has been overcome by slight initial movement of the spindles the fluid-pressure tends to complete the movement, reversing the apparatus and acting to balance the valves.

45 When a valve-face 10 becomes worn or it hardens, it can be readily removed and a new one substituted, and as the wear is very slight the valve-faces will wear for a long time.

50 Any other suitable means may be employed for imparting longitudinal movement to the valve-spindles, and my invention is not restricted to the device herein shown.

Having fully described my invention, what 55 I claim, and desire to secure by Letters Patent, is—

1. In an apparatus of the class described, a valve-case having inlet, exhaust and discharge chambers, oppositely-located ports in 60 the inlet and exhaust chambers, communicating directly with the discharge-chambers, a double valve within the inlet-chamber between the ports thereof, a valve in each discharge-chamber opposite the port in the 65 exhaust-chamber, and manually-operated means to impart positive initial movement

simultaneously and in the same direction to all of the valves, the fluid-pressure in the chambers completing the valve movement and retaining the valves in position to establish 70 communication between the inlet and one discharge chamber, and the exhaust and the other discharge chamber, and vice versa.

2. In an apparatus of the class described, a valve-case, discharge-chambers therein at 75 or near its ends, interposed common inlet and exhaust chambers, ports communicating with the discharge-chambers, a reciprocable double valve within the inlet-chamber, to control communication with the discharge-chambers, 80 the pressure of the fluid within said inlet-chamber acting to complete movement of and hold the valve seated, a valve movable in each discharge-chamber to control the exhaust therefrom, spindles on which the valves 85 are mounted, and manually-operated means to positively reciprocate said spindles to operate the valves simultaneously.

3. In an apparatus of the class described, a valve-case having inlet, exhaust and discharge chambers, oppositely-located ports in the inlet and exhaust chambers, communicating with the discharge-chambers, two valve-spindles extended through said ports, and having bearings in the case ends, valves on 90 one of said spindles within the discharge-chambers, to coöperate with the adjacent port-seats, a double valve on the other spindle within the inlet-chamber, and mechanically-operated means to positively and simultaneously reciprocate the spindles at will. 95

4. In an apparatus of the class described, a valve-case having inlet, exhaust and discharge chambers, oppositely-located ports in the inlet and exhaust chambers, communicating with the discharge-chambers, valve-spindles extended through said ports and having bearings in the case ends, said spindles having threaded portions, a double valve adjustable on one spindle within the inlet-chamber, two adjustable valves on the other spindle, in said discharge-chambers, and mechanically-operated means to positively move the spindles longitudinally and simultaneously, substantially as described. 105

5. In an apparatus of the class described, a valve-case having inlet, exhaust, and discharge chambers, ports in the inlet and exhaust chambers communicating directly with the discharge-chambers, valves coöoperating 110 with the ports in said inlet and exhaust chambers, and mechanical means to impart at will positive movement simultaneously and in one or the other direction to all of the valves, to direct the outflow of fluid from the casing 115 through one or other of the discharge-chambers, substantially as described.

6. In an apparatus of the class described, a valve-case having inlet, exhaust, and discharge chambers, ports in the inlet and exhaust chambers communicating directly with the discharge-chambers, valves coöoperating 120

with the ports in said inlet and exhaust chambers, and mechanical means to at will impart positive initial movements simultaneously and in one or the other direction to all of the 5 valves, the fluid-pressure in the chambers completing the valve movement and retaining the valves in position to establish communication between the inlet and one discharge chamber, and the exhaust and the

other discharge chamber, and vice versa, substantially as described.

In testimony whereof I have signed my name to this specification in the presence of two subscribing witnesses.
